UNITED STATES PATENT OFFICE.

HAMLET E. FORREST, OF NEW YORK, N. Y., ASSIGNOR TO WATSON & STILLMAN, OF SAME PLACE.

PACKING FOR STUFFING-BOXES.

SPECIFICATION forming part of Letters Patent No. 445,693, dated February 3, 1891.

Application filed July 25, 1890. Serial No. 359,895. (No model.)

To all whom it may concern:

Be it known that I, HAMLET E. FORREST, of the city of New York, in the county and State of New York, have invented a certain new and useful Improvement in Packing for Stuffing-Boxes, of which the following is a specification.

My invention relates to an improvement in packing for stuffing-boxes, the object being to provide means for preventing the escape of steam or other fluid from the cylinder to the outside of the packing at the point where the packing engages the stuffing-box, and to further provide for the adjustment of the packing to stuffing-boxes in which the seats are more or less irregular through wear or other causes.

A practical embodiment of my invention is represented in the accompanying drawings, 20 in which—

Figure 1 represents a sectional view of a stuffing-box, gland, and packing, with the rod therein; and Fig. 2 is a sectional view in detail of a two-part valve-ring.

25 A represents the stuffing-box, and B the gland for securing the packing within the stuffing-box. The main body of the packing is composed of separate rings C, of well-known construction, having their adjoining sides 30 beveled in order to adjust themselves in position to form an effective stop for the steam or other fluid which may tend to escape from the cylinder alongside of and in immediate proximity to the piston-rod D and held in position by suitable springs c. The springs c are preferably located between the flange G on the gland B and the heads of the fastening-bolts g, but may be inserted between the sets of packing, as is common.

35 40 To guard against the liability of the steam or other fluid escaping through the end of the stuffing-box along the space d, which it is found desirable to leave for any lateral vibration or play of the piston-rod into the 45 space b, between the wall of the stuffing-box and the outside of the packing C, I provide a valve-ring E, having its extreme diameter less than the diameter of the interior of the

stuffing-box and having its interior fitted as closely as may be to the piston-rod. The valve-ring E has its upper face beveled, as shown at e, for receiving the beveled edges on the rings C.

The valve-ring E is seated upon a seat-ring f. The upper flat face of the seat-ring f is 55 fitted, preferably by a ground joint, to the under flat face e' of the valve-ring E, and the lower face of the said seat-ring is adapted to rest in the end of the stuffing-box, where it may be made tight by the interposition between it and the end of the stuffing-box of a suitable cement or packing—such, for instance, as what is known as "usudurian." In order to insure a tight joint between the seat-ring and the end of the stuffing-box F', I provide the bottom of the seat-ring f with a bevel slightly greater than that of the end of the stuffing-box F', so that its inner edge will be sure to seat in close contact with the inner edge of the end F', the space between it and 70 the end of the stuffing-box where it recedes therefrom being tightly closed by the cement or packing. The exterior f' of the seat-ring f is fitted as close as may be to the wall of the stuffing-box for the purpose of preventing 75 any considerable lateral vibration of the seat-ring. The outer margin of the upper face of the seat-ring is cut away, as shown in Fig. 1, so as to leave the annular flat seat upon which the valve-ring rests substantially the same 80 width as the lower bearing-surface on the valve-ring.

While the valve-ring E is held in place under the pressure of the springs and effectually prevents the escape of the steam or fluid 85 under normal pressure, it may be lifted by any water collected in the cylinder and forced against it by the piston.

What I claim as my invention is—

The combination, with the stuffing-box, the 90 piston-rod, and the packing, of the valve-ring at the end of the packing, the seat-ring having one face upon which the valve-ring has a sliding engagement, and its opposite face toward the end of the stuffing-box adjacent 95 to the cylinder-head being beveled, so as to

recede from its seat as it extends outwardly from the piston-rod and form a space for cement or permanent packing, and its face toward the valve-ring being of substantially the same width as the adjacent face of the valve-ring, the outer margin of its said upper bearing-face being spaced from the inner

wall of the stuffing-box, substantially as set forth.

HAMLET E. FORREST.
